Patented Oct. 30, 1917.

Inventor:
Joseph Eifel
By authority
Paul Carpenter

UNITED STATES PATENT OFFICE.

JOSEPH EIFEL, OF CHICAGO, ILLINOIS.

WRENCH.

1,244,967.

Specification of Letters Patent. Patented Oct. 30, 1917.

Original application filed June 26, 1912, Serial No. 706,079. Divided and this application filed April 8, 1916. Serial No. 89,959.

To all whom it may concern:

Be it known that I, JOSEPH EIFEL, a citizen of the United States, and a resident of Chicago, in the State of Illinois, have invented certain new and useful Improvements in Wrenches, of which the following is a specification.

My present invention relates to wrenches in general and more particularly to wrenches having variable jaw openings, and has special reference to the provision of an improved wrench embodying the most valuable features of wrenches of a number of different types known to me, and avoiding the defects thereof.

The principal objects of my present invention are the provision of a wrench having jaws one of which may be rapidly moved relatively to the other, a wrench thus characterized which will not tend to work open in handling, thus requiring repeated settings or adjustments during a single operation, one which will have small crushing effect tending to abrade, flatten or otherwise disfigure articles upon which it is used; the provision of an improved plier form wrench adapted for wide separation of the jaws without concurrent wide opening of the handles and one wherein relatively slight manipulation is required either in moving the article acted upon or in obtaining a fresh hold thereupon; the provision of a wrench maintained irrespective of the size of the object operated upon; the provision of a wrench wherein the number of contact points of the jaws thereof with the article operated upon may be increased and generally to provide an improved and more efficient type of wrench than is at this time available, together with such further and additional objects as may hereinafter appear.

Certain embodiments of devices involving, in part, my present improvements, are shown in my co-pending application for Letters Patent, Serial No. 706,079, filed June 26, 1912, of which the present application is a division.

In gaining the objects above mentioned, as well as certain benefits and advantages to be below pointed out, I have provided the constructions illustrated in the accompanying drawings, wherein—

Figures 1 and 2 are respectively a plan view and an elevational view of a form of

wrench embodying my present improvements; 55

Figs. 3 and 4 are sectional views thereof, taken respectively on the lines 3—3 of Fig. 1 and 4—4 of Fig. 3;

Figs. 5 and 6 are elevational views of 60 modified types of jaws applicable to devices embodying my present improvements.

Referring now to the drawings it will be observed that I have here illustrated a wrench embodying my invention in the 65 form of adjustable parallel pliers, wherein a shank 10 has formed at one end a handle 11 and at the opposite end a jaw 12, and that the jaw 12 is slotted as indicated at 13 to allow the shank 14 provided with a 70 jaw 15 to move therein and support the jaw 15 in parallelism with the jaw 12. The shank is provided with toothed means for engagement with the jaw 15, here shown as the link 16^a, provided with ratchet teeth 16^a 75 engaging teeth 16^b on the jaw 15, the said shank 14 engaging the said link 16^a by means of a ball extension 22 engaging a socket 22^a. For moving said jaw 15 relatively to the jaw 12 I employ an operating 80 lever 17 formed on the shank 14 which is pivoted to the lever 10 as indicated at 18, and as an anti-friction device between the jaws 12 and 15 I employ a roller bearing indicated at 24.

For normally preventing movement of the jaw 15 relative to the link 16^a, and thereby lineal movement of such jaw relatively to the shank 14 and consequently separation of the jaws 12 and 15, I employ a lever 78 90 pivoted to the handle 10 as indicated at 80, and engaging by means of a pin 76 a slot 77 formed in the link 16^a, the shank 10 being slotted as indicated at 81 to permit movement of said pin in the shank 10, and for 95 normally holding the lever 78 in position and thereby the link 16^a in engagement with the toothed surface of the jaw 15, I employ a slide 79 engaging a slot 79^a and acting on one surface of the end of said lever 78, a 100 spring 82 bearing on the opposite surface thereof serving to throw the toothed portions of the members 16 and 15 out of engagement when said slide is moved to the right in Fig. 2, thereby permitting adjustment of the jaw 15 relatively to the jaw 12. 105

To permit a partial movement of the lever 78 sufficient merely to allow a ratcheting of

the toothed portion of the member 15 upon the toothed portion of the member 16, a notch 83 is provided in the lever 78 but if entire disengagement is desired the slide 5 should be moved to the right so that the boss 84 formed thereupon will approximate the position of the surface 85 of such lever. A spring 86 normally serves to aid in holding the link 16 in contact with the jaw 15 and a pin 87 passing through the slot 77 serves to limit the movement of said link toward said jaw.

Where desirable the device of Fig. 1 may be provided with jaws having cutters as indicated at 45^b, 46^b, in Fig. 5, or with jaws curved or serrated, or both, as indicated at 47^b, 48^b, in Fig. 6.

From the foregoing description of the construction and operation of the present embodiment of my invention, it will be observed that the type here disclosed is provided with means whereby the jaws may be instantly opened and closed to a limited extent for shifting relatively to the work, thereby making it feasible to utilize notches such as 50-51 for the purpose of engaging the corners, as well as flat faces of nuts, giving a much firmer hold thereupon. Since the pressure applied upon closing the wrench 20 may be very readily varied, it is obvious that the pressure applied to any nut, pipe or other object worked upon may be gaged to suit conditions with the greatest of facility. Other advantages of my present invention will be apparent to those who are skilled 25 in the art to which it pertains.

Having thus described my invention and illustrated its use, what I claim is new and desire to secure by Letters Patent is:

40. 1. A device of the character described comprising, in combination, a pair of co-operating jaws, pivoted operating levers therefor, one of said jaws being movable transversely of the longitudinal axis of the device and relatively to its lever and having pawl and ratchet means for releasable engagement therewith whereby the extent of the jaw opening may be varied.

2. A device of the character described comprising, in combination, a pair of co-operating jaws, pivoted operating levers therefor, one of said jaws being movable relatively to the other thereof and to its lever and provided with a ratchet portion, and a pawl for releasably engaging said ratchet portion, and means for positively but releasably holding said pawl in engagement with said ratchet portion whereby the jaws may be held in predetermined operative relation to each other.

3. A device of the character described comprising, in combination, a pair of co-operating jaws, operating levers therefor, a pivotal connection between said levers, one of said jaws being movable rela-

tively to its lever and both the lever and the jaw being provided with means for engagement, an intermediate member engaging said means, whereby the relative position of the jaws may be varied, and means for positively holding the jaws in predetermined operative relation to each other including said intermediate member and a third lever provided with means engaging said intermediate member.

4. A device of the character described comprising, in combination, a pair of co-operating jaws, operating levers therefor, a pivotal connection between said levers, one of said jaws being movable relatively to its lever and both the lever and the jaw being provided with means for engagement, an intermediate member engaging said means whereby the relative position of the jaws may be varied, and means for positively holding the jaws in predetermined operative relation to each other including said intermediate member and a third lever provided with means engaging said intermediate member and a spring for maintaining such engagement.

5. A device of the character described comprising, in combination, a pair of co-operating jaws, pivoted operating levers therefor, one of said jaws being movable relatively to the other thereof and to its lever and provided with engaging means, an intermediate member operated by said lever, and means for releasably engaging said engaging means and intermediate member whereby the jaw and its operating lever may be held in predetermined operative relation to each other.

6. A device of the character described comprising in combination a pair of co-operating jaws, operating levers therefor, one of said jaws being movable transversely of the longitudinal axis of the device, and a member intermediate between said movable jaw and its operating lever whereby the position of the said jaw may be changed relatively to its lever without moving the latter.

7. A device of the character described comprising in combination a pair of co-operating jaws, operating levers therefor, one of said jaws being slidably relative to the other transversely of the longitudinal axis of the device and a member intermediate between said jaw and its operating lever whereby the position of the said jaw may be changed relative to its lever without moving the latter.

8. A device of the character described comprising in combination a pair of co-operating jaws, pivoted operating levers therefor, one of said jaws being movable transversely of the longitudinal axis of the device, a member intermediate between said jaw and its operating lever whereby the

- position of the said jaw may be changed relatively to its lever without moving the latter, and releasable means for positively locking said intermediate member in engagement with its lever and jaw. 70
9. A device of the character described comprising in combination a pair of coöperating jaws, one of said jaws being adapted to slide relatively to the other transversely of the longitudinal axis of the device, a lever pivotally connected to the shank of the fixed jaw for operating the said slideable jaw and an intermediate member adapted to connect said lever and movable jaw and means for adjusting the position of said member relatively to said jaw. 75
10. A device of the character described comprising in combination a pair of coöperating jaws, one of said jaws being adapted to slide relatively to the other transversely of the longitudinal axis of the device, a shank attached to one of the said jaws, a lever pivotally attached to said shank and adapted to coöperate therewith to move the other jaw relative to the first mentioned jaw, and a link connection between the said lever and the movable jaw. 80
11. A device of the character described comprising, in combination, a pair of coöperating jaws adapted to slide relatively to each other, an operating lever rigidly connected to one of said jaws, one of said jaws being movable relatively to the other and provided with a ratchet portion, and a pawl for releasably directly engaging said ratchet portion whereby the jaws may be held in predetermined operative relation to each other, and a second lever operatively connected to said pawl adapted by movement relatively to said first lever to move said jaws relatively to each other. 85
12. A device of the character described comprising, in combination, a pair of coöperating jaws adapted to slide relatively to each other, an operating lever rigidly connected to one of said jaws, one of said jaws being movable relatively to the other and provided with a ratchet portion, and a pawl for releasably engaging said ratchet portion whereby the jaws may be held in predetermined operative relation to each other, and a spring adapted to move said pawl in one direction relatively to said toothed portion, and manually operated means adapted to move said pawl in the opposite direction, and a second lever operatively connected to said pawl adapted by movement relatively to said first lever to move said jaws relatively to each other. 90
13. A device of the character described comprising, in combination, a pair of coöperating jaws adapted to slide relatively to each other, an operating lever rigidly connected to one of said jaws, one of said jaws being movable relatively to the other and provided with a ratchet portion, and a pawl for releasably engaging said ratchet portion whereby the jaws may be held in predetermined operative relation to each other, and a second lever operatively connected to said pawl adapted by movement relatively to said first lever to move said jaws relatively to each other. 95
14. A device of the character described comprising, in combination, a pair of coöperating jaws, an operating lever connected to one of said jaws, one of said jaws being movable relatively to the other and provided with a ratchet portion, and a pawl for releasably directly engaging said ratchet portion whereby the jaws may be held in predetermined operative relation to each other, and a second lever operatively connected to said pawl adapted by movement relatively to said first lever to move said jaws relatively to each other, a manually-operated lever adapted to control the position of said pawl relatively to said toothed portion. 100
15. A device of the character described comprising, in combination, a pair of coöperating jaws, an operating lever connected to one of said jaws, one of said jaws being movable relatively to the other and provided with a ratchet portion, and a pawl for releasably engaging said ratchet portion whereby the jaws may be held in predetermined operative relation to each other, and manually-operated means adapted positively to lock said pawl and ratchet portion in engagement with each other. 105
16. A device of the character described comprising, in combination, a pair of coöperating jaws, pivoted operating levers therefor, one of said jaws being movable relatively to the other thereof and to its lever and provided with a toothed portion, and a pawl for releasably engaging said toothed portion whereby the jaws may be held in predetermined operative relation to each other, and means for positively holding said pawl both in and out of engagement with said toothed portion. 110
17. A device of the character described comprising, in combination, a pair of coöperating jaws, pivoted operating levers therefor, one of said jaws being movable relatively to the other thereof and to its lever and provided with a toothed portion, and a pawl for releasably engaging said toothed portion whereby the jaws may be held in predetermined operative relation to each other, and means for positively holding said pawl in engagement with said toothed portion. 115
18. A device of the character described comprising, in combination, a pair of coöperating jaws, pivoted operating levers therefor, one of said jaws being movable relatively to the other thereof and to its lever and provided with a toothed portion, and a pawl for releasably engaging said toothed portion whereby the jaws may be held in predetermined operative relation to each other, and means for positively holding said pawl in engagement with said toothed portion. 120
19. A device of the character described comprising, in combination, a pair of coöperating jaws, pivoted operating levers therefor, one of said jaws being movable relatively to the other thereof and to its lever and provided with a toothed portion, and a pawl for releasably engaging said toothed portion whereby the jaws may be held in predetermined operative relation to each other, and means for positively holding said pawl in engagement with said toothed portion. 125
20. A device of the character described comprising, in combination, a pair of coöperating jaws, pivoted operating levers therefor, one of said jaws being movable relatively to the other thereof and to its lever and provided with a toothed portion, and a pawl for releasably engaging said toothed portion whereby the jaws may be held in predetermined operative relation to each other, and means for positively holding said pawl in engagement with said toothed portion. 130

15
5
tively to the other thereof and to its lever and provided with a toothed portion, and a pawl for releasably engaging said toothed portion whereby the jaws may be held in predetermined operative relation to each other, and means for positively holding said pawl out of engagement with said toothed portion independently of the position of the jaw operating levers.

19. A device of the character described comprising, in combination, a pair of coöperating jaws, one of said jaws being adapted to slide relatively to the other transversely

of the longitudinal axis of the device, pivoted operating levers therefor, one of said jaws being movable relatively to the other thereof and to its lever and releasable means for positively preventing movement of said last mentioned jaw relatively to its lever.

20
In testimony whereof I have hereunto signed my name in the presence of the two subscribing witnesses.

JOSEPH EIFEL.
